UNITED STATES PATENT OFFICE

1,988,874

ABRASIVE SURFACING DISK

James A. Malcolm, Chicago, Ill., assignor to
Julius S. Neale, Chicago, Ill.

Application February 20, 1933, Serial No. 657,535

2 Claims. (Cl. 51—195)

This invention relates to improvements in an abrasive surfacing disk, and is more particularly directed to an improved composite abrasive disk for use in the surfacing and abrading of metal, 5 wood and other surfaces, on articles such as sheet metal bodies, floors and numerous other articles having a surface which must be cut down to a smooth and generally level condition.

In the operation of such devices, the disk is 10 secured at its center to a rotating shaft and the outer portion of the disk, which is covered on its operating surface with a suitable abrasive, is then pressed against the work, and particularly where the operation is carried out on metal there 15 is an extremely high resistance to the rotation of the disk by reason of the cutting of the abrasive grains into the metal. The result is that the disks, in order to have a suitable life, must be made of extremely strong tough material, which 20 at the same time must have a certain degree of flexibility to permit them to flex and bend as the supporting pad compresses or bends. It is essential that the material be capable of withstanding alternate bending or flexing at a high rate of 25 speed and without the separation of one layer of the composite material from another.

It is, therefore, the main object of this invention to provide an improved composite abrasive disk of the character described which is formed 30 of a compressible material having an abrasive surface so secured thereto as to withstand alternate bending or flexing at a high rate of speed without the separation of one layer of the composite material from another.

Another object of this invention is to provide a composite abrasive disk of the character described including a compressible felt body, to one surface 35 of which is securely fastened a canvas disk to the free surface of which canvas disk is adhesively secured a layer of abrasive grains.

A further object of this invention is to provide a composite abrasive disk of the character described, including a relatively thick body of compressible material, upon one surface of which is 45 adhesively secured a layer of grains, said layer of grains extending to and covering the outer edge of said disk.

A still further object of this invention is to provide a composite abrasive disk of the character 50 described which is formed of a compressible material, to one surface of which is rigidly secured by stitching or the like a canvas disk, and to the outer surface of said canvas disk is adhesively secured a layer of grains, said layer of grains also 55 covering the outer free edge of said disk.

A still further object of this invention is to provide a composite abrasive disk of the character described which is formed of a compressible material having a relatively thick body for providing the desired flexibility to permit the disk to bend and flex, but at the same time being capable of withstanding alternate bending or flexing at a high rate of speed and without the separation of one layer of the composite material from another, said disk being also capable of being 10 resurfaced with said abrasive grains whenever found necessary or desirable.

A still further object of this invention is to provide a composite abrasive disk of the character described having a body of compressible material, to one surface of which is permanently secured a layer of abrasive grains, said body being capable of being resurfaced from time to time as such abrasive grains are worn away in use.

A still further object of this invention is to provide a composite abrasive disk of the character described which is simple in construction and which may be produced along lines convenient for low cost manufacture, and which may be highly efficient for carrying out the purposes 25 for which it is designed.

With the foregoing and other objects in view, which will appear as the description proceeds, the invention consists in certain novel features of construction, arrangement and combination of 30 parts, hereinafter more fully described, illustrated in the accompanying drawing, and particularly pointed out in the appended claims, it being understood that various changes in the form, proportion, size and minor details of the structure may be made without departing from the spirit or sacrificing any of the advantages of the 35 invention.

For the purpose of facilitating an understanding of my invention, I have illustrated in the foregoing drawing a preferred embodiment thereof, from an inspection thereof when considered in connection with the following description, my invention, its mode of construction, assembly and operation, and many of its advantages, should be 40 readily understood and appreciated.

Referring to the drawing in which the same characters of reference are employed to indicate corresponding or similar parts throughout the several figures of the drawing:

Figure 1 is a view in perspective of my improved surfacing disk, the same being shown connected to an apparatus by means of which the disk is rotated;

Fig. 2 is a transverse central section through 55

one form of my improved disk, being taken on line 2-2 of Fig. 4;

Fig. 3 is a transverse central section through a modified form of my improved disk, taken on line 3-3 of Fig. 5;

Fig. 4 is a bottom plan view of the modification shown in Fig. 2; and

Fig. 5 is a bottom plan view of the modified form shown in Fig. 3.

- 10 As already stated, the present invention is directed primarily to the provision of an abrasive disk for use on a rotatable shaft. As shown in Fig. 1, there is provided a shaft 1 upon the free end of which is mounted my improved flexible abrasive covered disk 10, said shaft and disk being secured to a housing 2 and are rotated by the flexible shaft 3 which is carried to the housing 2 where it drives the shaft 1 through suitable bevel gears (not shown). The housing 2 is provided with a suitable handle 4 by means of which the operator holds the device against the work, thus giving him a quite accurate control of the operation as he can both vary the pressure of the abrasive disk against the work or vary the angle 25 at which the apparatus works, and also move the operating portion of the abrasive disk from point to point over the surface of the panel in order to prevent the warping which results in the case of certain metal panels if the disk is held in 30 one position too long.

In the form illustrated in Fig. 2, my improved disk comprises a body 11 which may be formed of any suitable compressible material, such as felt, which had been securely stitched together by 35 means of stitching 12 and then compressed to the desired thickness. To one surface of this pad 11 is then secured a layer of adhesive 13 to which latter is then secured a layer of abrasive grains 14, said layer of adhesive and grains extending 40 to the outer edge 15 of the disk. The composite structure thus formed is provided with a central opening 16 which illustrates the simplest means for permitting attachment of this disk to the driving shaft 1.

45 From my experience in the manufacture and sale of abrasive disks of this character, and from numerous tests conducted with these disks, I have found that a composite disk of the structure referred to above and more particularly illustrated in Fig. 2, will possess all of the qualities required in such an article, that is, flexibility, the torsional strength under the resistance set up by the engagement between the abrasive grains and the work, and the life which is necessary for economical operation of such machines under the above strains and under alternate flexure when the speed of rotation does not exceed about seventeen hundred revolutions per minute.

However, when it is desired to produce a disk of 60 this character which will possess the above qualities and will stand up under a speed of revolutions greater than seventeen hundred revolutions per minute, say up to and including thirty-five hundred revolutions per minute, I have found it desirable to secure the abrasive grains to a canvas disk and then adhesively secure the layer to the felt pad. Thus in the modification illustrated in Figs. 3 and 5, there is shown a pad 20 which is made up of compressible material, such as felt, which material is securely stitched together by 65 means of the radial rows of stitches 21 and then

compressed to the desired thickness. To one face of this felt disk is then secured a layer of adhesive 22, to which layer is then secured a canvas disk 23, which canvas disk may be further secured to the felt pad 20 by means of the circumferential rows of stitching 24, whereby the canvas disk may be rigidly and permanently secured to the felt body.

The disk of canvas 23 is substantially of the same shape and size as the felt pad, and to the outer surface thereof is applied a layer of adhesive 25 to which layer is secured a layer of abrasive grains 26. The abrasive 26 is adapted to extend around the outer rim of the disk, as shown at 27 in Fig. 3. The composite structure 15 thus formed is provided with a central opening 28, which illustrates the simplest means for permitting attachment of this disk to a supporting and driving shaft.

From the above it will be apparent that I have 20 provided an abrasive disk which will have the desired degree of flexibility to permit the same to bend and flex while at the same time being capable of withstanding alternate bending or flexing at a high rate of speed and without the separation 25 of one layer of the composite material from another. It will also be noted that by reason of the pad of felt provided for the abrasive material a cushioning effect will be produced in the operation of the device, thereby eliminating the necessity for a cushioning pad of rubber or the like heretofore used with devices of this character.

30 A further feature of this construction is that the pad may be resurfaced from time to time as the abrasive is worn therefrom in the use of the 35 pad. This is a feature which has not been possible with abrasive disks heretofore produced, and as a result of this feature a considerable saving may be made in the operation and use of surfacing disks of this character.

40 It is believed that my invention, its mode of construction, assembly and operation, and many of its advantages should be readily understood from the foregoing without further description, and should also be manifest that while preferred 45 embodiments of the invention have been shown and described for illustrative purposes, the structural details are nevertheless capable of wide variation within the purview of my invention as defined in the appended claims.

50 What I claim and desire to secure by Letters Patent of the United States is:

1. A composite surfacing disk comprising a pad of compressible material which had been compressed and stitched to form a relatively stiff and rigid element, a sheet of cloth secured to said pad both by stitching and adhesive extending over its entire area, and a coating of grains adhesively secured over the free surface of said cloth and over the outer edge of said pad.

2. A composite surfacing disk, comprising a pad of compressible material which had been compressed and stitched to form a relatively stiff and rigid element, a coating of adhesive substance applied to said element and extending over the entire surface of one face thereof and the outer periphery thereof, and a coating of grains adhesively secured to said adhesive coating to cover the entire area thereof, including the outer periphery of said element.

70 JAMES A. MALCOLM.
